Primary Examiner — Michael A Pratt(74) *Attorney, Agent, or Firm* — Studebaker & Brackett PC(57) **CLAIM**

The ornamental design for tie rod and nut, as shown and described.

DESCRIPTION

FIG. 1 is a top view showing my new design for tie rod and nut,

FIG. 2 is a side view of the nut, the opposite side being a mirror image thereof,

FIG. 3 is a top view thereof, the bottom view being a mirror image thereof,

FIG. 4 is a rear view thereof,

FIG. 5 is a front view thereof,

FIG. 6 is a front perspective view thereof,

FIG. 7 is a rear perspective view thereof,

FIG. 8 is a perspective view of the tie rod,

FIG. 9 is a greatly enlarged view of the left side view thereof, the ends of the tie rod are shown broken away for ease of illustration,

FIG. 10 is a greatly enlarged view of the right side view thereof, the ends of the tie rod are shown broken away for ease of illustration,

FIG. 11 is a front view thereof; and,

FIG. 12 is a rear view thereof.

The design is shown broken apart along its length to indicate that no specific length is claimed.
